UNITED STATES PATENT OFFICE.

JOHN H. HOMRIGHOUSE, OF OAK PARK, ILLINOIS, ASSIGNOR, BY MESNE ASSIGNMENTS, TO AUTOMATIC ELECTRIC INC., OF CHICAGO, ILLINOIS, A CORPORATION OF DELAWARE.

AUTOMATIC TELEPHONE SYSTEM.

Application filed June 24, 1918. Serial No. 241,516.

My invention relates to improvements in automatic telephone systems and more particularly to an improved method of controlling non-numerical switches of the type employed in completing connections between calling lines and trunk lines. It has usually been customary in the commercial operation of switches of this type to preselect only one idle trunk line for a group of lines before a call originates in such group and it quite frequently happens that if two subscribers remove their receivers at the same instant, the individual switches of these subscribers who have thus removed their receivers will 10 operate simultaneously to seize the same trunk line.

An object of my invention is, therefore, to partially overcome the difficulty explained above by providing means for preselecting 20 a second idle trunk line.

A further object of my invention is the provision, in a system in which non-numerical switches are controlled by master switches of the reciprocating type, of means 25 whereby the master switches control the non-numerical switches in such a manner that certain of the non-numerical switches will have access to one idle trunk line, while the rest of the non-numerical switches in the 30 group will have access to another idle trunk line at the same time, with a view to reducing the time interval required for interconnecting calling lines and trunk lines.

Further objects of my invention relate to 35 certain improvements in the various switches employed all of which will be more readily understood by reference to the accompanying drawings, in which I have illustrated my invention in connection with an automatic telephone system embodying automatic switches of the well known type.

Fig. 1 indicates a calling substation A, whose line conductors 12 and 13 have been extended through the medium of the individual line switch C, and secondary line switch D to a trunk line terminating in a selector switch E.

Fig. 2 indicates a calling substation A' in another group of lines whose line conductors 112 and 113 have been extended through the medium of the individual line switch C' and secondary line switch D' in the same group as secondary line switch D, to a trunk line terminating in a selector switch E'.

Fig. 3 is a diagrammatic view showing the 55 manner in which the primary and secondary switches are grouped and trunking connections to groups of first selector switches. In the figure the individual switches C and C' of all the lines in the system are shown arranged in groups h, h', etc., usually one hundred in a group having common access to a small number of trunk lines which lead to secondary switches D and D'. These secondary switches are arranged in groups j, j', etc., like the primary switches, each group having access to a small number of trunk lines leading to selector switches E and E'. These first selector switches are arranged in groups l, l', etc., usually ten in a group having 60 access to other selector switches or connector switches. The trunks leading from any one primary board do not lead to any one secondary board, but are distributed over a plurality of secondary boards. Likewise 65 the trunks leading from any one secondary board do not lead to any one group of first selector switches, but are distributed over a plurality of groups of selector switches.

Fig. 4 represents a perspective view of 80 certain mechanical parts of the improved switch. The frame and other unnecessary parts are omitted for clearness in illustration and description.

Figure 5 shows a side elevation of the controlling arm 290 and the locking plate 229 in a position just before the vertical member 290^a comes into contact with the locking plate 229.

Referring to Fig. 4, 86 designates a shaft 90 mounted on a supporting structure (not shown). The shaft 86 has a relatively long vertical member 86^a mounted on horizontally extending arms from the axis thereof. The vertical member 86^a is adapted to engage a notch in the sector shaped member of the plunger 67^a so that the rotation of the shaft will move the plunger 67^a together with similar plungers in a horizontal plane. The upper end of shaft 86 is provided with a sector 95 shaped controlling plate 85; the wide end of locking plate 85 is provided with notches adapted to be engaged by the controlling arm 83 in a manner hereinafter described. The lower end of the shaft 86 is provided with a 100 controlling arm 290 which extends horizontally from the axis of the shaft 86 and is provided with a vertical projecting member 290^a.

adapted to engage the locking plate 229 on the upper end of shaft 230. The vertical member 290^a is provided with an insulated knob adapted to operate the springs mounted upon the locking plate 229. The shaft 86 rotates in a counter-clock-wise direction by the tension of spring 97 and in a clock-wise direction controlled by the solenoid 265 to be hereinafter more fully described.

10 The shaft 230 is similar to shaft 86 except that it is rotated in a clock-wise direction by the engagement of the vertical member 290^a contacting the locking plate 229, all of which will be more fully hereinafter 15 described.

The automatic substations A and A' may be of any suitable or approved type, such for example, as the substation shown in the British patent to Martin, No. 1,419, of 1910. 20 Referring to the substation A, it comprises the usual receiver 7, transmitter 6, switch-hook 8, ringer 10 and condenser 11. Being an automatic substation, there is also provided a pair of impulse springs 4 and 5 controlled by an impulse wheel 9 through the medium of a finger hole dial (not shown). The primary line switches C and C' are of the general type of line switch shown in the British patent to R. W. James, No. 26,301, 30 of 1906, being, however, of the particular type shown in United States Letters Patent No. 1,078,690, granted January 17, 1912, to Frank Newforth. Through the medium of the line switch C the line of substation 35 A is given access to a plurality of trunk lines each terminating in a secondary switch.

The line switch C and a plurality of other line switches are controlled in their trunk selecting operations by means of a master switch F. Likewise, the line switch C' and a plurality of other line switches are controlled in their trunk selecting operations by means of the master switch F'. The master switches F and F' are of the general 45 type of master switch disclosed in the above mentioned British patent to James No. 26,301, of 1906, being however, more nearly of the particular type disclosed in United States Letters Patent No. 1,185,510, granted

50 May 30, 1916, to A. E. Keith. As is well known, the function of the master switch is to maintain the plungers of all the idle line switches which it controls in position before the terminals of idle trunk lines.

55 The secondary line switches D and D' are similar to the primary line switches C and C'. Through the medium of these secondary switches the trunk lines from the primary switches are extended to trunk lines 60 terminating in selector switches such as E and E'.

The line switches D and D' together with a plurality of similar switches are controlled in their trunk selecting operations by means 65 of a master switch I. The master switch I

is similar to the master switches F and F' except that the mode of operation is somewhat different and the circuits modified to operate in a system embodying the principles of my invention. As is usually the case 70 in switches of this type the plungers of all idle line switches which the master switch controls are in a position before the terminals of an idle trunk line. But I provide means whereby certain of the line switches 75 are in a position before one idle trunk while the remaining line switches which the master switch controls are in a position before a second idle trunk line.

Two trunk lines to which the secondary line 80 switches D and D' have access are indicated in the drawings Figs. 1 and 2, extending to the selector switches E and E', respectively, of which only the line and release relays are shown. The selectors E and E' may be 85 of the type shown in United States Letters Patent to Newforth No. 1,078,690.

While I have shown throughout the drawings a plurality of batteries it is to be understood that there may be but one battery 90 having its positive pole grounded.

Having given a general description of the apparatus involved in the system, I will now proceed to explain more in detail the 95 operations of the same.

When the receiver at substation A is removed from the switch hook preparatory to making a call, the engagement of the switch hook springs completes a bridge across the line conductors 12 and 13. The closure of this bridge across the line establishes an energizing circuit for the line relay 14 of the line switch C. Relay 14, upon energizing, closes a circuit for the pull-in winding 15 at springs 16 by way of common conductor 50. The pull-in winding, upon energizing, operates both the plunger arm 20 and the cut-off armature 21, the former through the medium of its plunger (not shown) forcing the bank springs 22 to 25, inclusive, into engagement, respectively, with contacts 26 to 29, inclusive, and the latter disconnecting the line relay and ground from the line conductors 12 and 13, respectively.

It is assumed that immediately prior to the removal of the receiver at substation A the plunger of the line switch C and all the other plungers of the idle line switches in the group were standing in a position before the terminals of the particular trunk line shown in the drawings and which extends to the secondary switch D. This being the case, the master switch wiper 34 would at that time have been in engagement with contact 35. The locking arm 36 would have been resting in notch 37 of the locking plate 38. With the master switch in this position as a result of the engagement of spring 24 with contact 28 a circuit for the starting relay 39 is closed by way of the master switch 130

wiper 34. Upon energizing, the starting relay completes a circuit which includes the low resistance winding of the supervisory relay 40 and the winding of relay 42 in series. 5 The locking relay 42, upon attracting its armature completes a circuit which includes the high resistance winding of relay 40 and the winding of relay 41 in parallel, and at the same time disengages the locking arm 10 36 from the notch 37, thereby allowing the plunger shaft 43 to rotate in a counter-clockwise direction under spring tension to the position shown in the drawing. The relay 41, upon energizing, disconnects battery from 15 the pull-in windings of all the line switches of the group while the master switch is moving their plungers to a new position in order to prevent the operation of any other line switch during that time. It is understood 20 that by the rotation of the shaft 43 in the manner described the plungers of all idle line switches are moved into position before the terminals of the ninth trunk line provided that such trunk line is not already 25 busy. Subsequent calls will now operate the master switch in the manner described until at such time when the plungers of all the idle line switches are before the terminals of the first trunk line, in which case a line 30 switch in seizing the first trunk will complete a circuit for the starting relay 39 in the usual manner as described above, but this relay upon energizing at this time completes a circuit for the relay 44 at springs 35 45 (pressed into engagement by arm 46) in parallel with the relay 42. The relay 44, upon energizing, completes a holding circuit for the locking relay 42 to maintain it energized after the wiper 34 has moved off of 40 the grounded contact associated with the first trunk, and also completes a circuit for the solenoid 47. The solenoid now draws in its plunger, thereby rotating the plunger shaft 43 in a clock-wise direction until the 45 wiper 34 and all the plungers of the idle line switches reach a position before the terminals of the tenth trunk line, whereupon the rotation will stop provided the tenth trunk is not busy. Although the circuit of relay 50 44 is at once broken as soon as the arm 46 begins to move, its springs are held in an operated position by the detent 48 until the apparatus reaches the position where the plungers are before the terminals of the tenth trunk in which case the detent is disengaged by the arm 49. 55 As a further result of the engagement of spring 24 with contact 28 an energizing circuit is completed for the pull in winding 60 55 of the secondary line switch D, as follows: springs 69 and 70, slow acting relay 56, common conductor 68, springs 57, windings 62 and 63 of relay 58, springs 59 and low resistance winding of supervisory relay 65 66. Relay 56 operates at this time to close a holding circuit for the winding 73 of the line switch C to prevent it from releasing. Relay 58, upon energizing, shorts its high resistance winding 62, thereby allowing sufficient current to flow through the pull-in 70 winding 55 to operate the plunger arm 67. By the engagement of spring 71 with spring 69 a holding circuit is completed for the windings 55 and 72 of the secondary line switch in series over the trunk conductor 75 32. The circuit of relay 56 is opened at springs 69 and 70, but being slow to release its armature, it maintains the temporary holding circuit over the release trunk conductor 31 for winding 73 of the line switch 80 C until the plunger arm 67 through the medium of its plunger (not shown) forces the bank springs 51 to 54 inclusive, into engagement with contacts 74 to 77, inclusive, whereupon a circuit is completed for the 85 line relay 78 of the selector switch D, over trunk conductor 30, contact 26, spring 22, line 12, to and through substation A, line conductor 13, spring 25, contact 29, and trunk conductor 33. Relay 78, upon energizing, closes a circuit for release relay 79. Relay 79, upon energizing, completes a holding circuit for winding 73 of line switch C at springs 80, also closes a circuit for the 90 chain relay 232, in parallel with the winding 73. Accordingly, relay 232 energizes and completes at contacts 242 one point in the circuit of stop relay 65. However, the circuit of relay 65 includes similar contacts on 95 nine other chain relays, one for each of the other trunks in the group, and relay 65 does not, therefore, pull up at this time. Of these chain relays, only chain relays 231, 232, and 240 are shown. 100 Also the chain relays 231, 232, etc., upon energizing, short the resistance coils 271, 272, etc., at springs 251, 252, etc. respectively, for a purpose to be hereinlater described. 105 It is assumed that all the plungers of the idle secondary switches in engagement with the shaft 86 were standing in a position before the terminals of the particular trunk line shown in the drawing just before the operation of the line switch D. This being 110 the case the master switch wiper 81 would at that time have been in engagement with contact 82, the locking arm 83 would have been resting in notch 84 of locking plate 85, and as it has heretofore been stated an object of the master switch I is to maintain 115 the plungers engaged by the shaft 86 in a position before the terminals of an idle trunk, while the plungers engaged by the shaft 230 are in a position before the terminals of a second idle trunk in the same group of trunks; therefore the master switch wiper 225 would be in engagement with contact 226. The locking arm 227 might well 120 be resting in notch 228 of the locking plate 125 130

229. The rotation of the locking plate 85 together with the shaft 86 in a counter-clock-wise direction does not cause the plunger shaft 230 to move.

5 As a result of the engagement of spring 53 with contact 76, ground potential is placed upon contact 82 and its corresponding contact in the bank which master switch wiper 225 has access to, thereby making the trunk 10 line associated with that contact busy. Accordingly, a circuit is completed for winding 87 of starting relay 89 by way of wiper 81. Relay 89, upon energizing, opens the 15 circuit of relay 60 at springs 94 and 95, and closes a circuit at springs 95 and 96 for slow acting relay 61 and locking relay 90 in parallel. Relay 90 upon attracting its armature completes a circuit for the high resistance winding of supervisory relay 66, also at the same time disengages the locking 20 arm 83 from the notch 84, thereby allowing the plunger shaft 86 to rotate in a counter-clock-wise direction by the tension of the spring 97 to the position shown in the 25 drawing. The relay 61, upon energizing, disconnects battery from the common relay 58 in order to prevent the operation of any other line switches in engagement with the shaft 86 during the time that the plunger 30 shaft is rotating. By the rotation of the shaft 86 in the manner described above all the plungers of the idle line switches in engagement with the shaft 86 are moved to a 35 position before the terminals of the eighth trunk line, provided that such trunk line is not already busy. The operation of other line switches whose plungers are engaged by shaft 86 will operate the master switch in the same manner as described above until 40 the plungers engaged by the shaft are in a position before the terminals of the first trunk line, in which case a secondary switch in operating to seize the first trunk line will cause the master switch to rotate in a 45 clock-wise direction which will be more fully described hereinafter.

The foregoing operations have all taken place in response to the removal of the receiver at substation A. The calling subscriber may now proceed to operate his calling device in accordance with the digits of the desired number whereby the selector E and succeeding switches are actuated in the regular manner to complete the required connection.

50 I will now explain how the subscriber at substation A' by the removal of the receiver from the switch hook upon initiating a call will establish a connection with the first selector switch E' through the medium of his individual line switch C' and the secondary line switch D'. As the operations of the 55 primary switch C', secondary switch D' together with the master switch F' is the same as that described in connection with the pri-

mary switch C, secondary switch D, and master switch F, respectively, also as similar reference characters have been given to like parts it is not thought necessary to describe the operations in detail. So I will proceed 70 at once to describe the operation of the master switch I when the trunk line terminating in the first selector switch E' is seized by the operation of the secondary switch D'. It having been assumed that immediately 75 prior to the operation of secondary switch D' all the plungers of the idle line switches in engagement with the shaft 230 were standing before the terminals of the trunk line leading to the selector E'. The operation of the plunger arm 167 through the medium of its plunger (not shown) forces the bank springs 151 to 154, inclusive, into engagement with contacts 174 to 177, inclusive. The engagement of spring 153 with contact 176 places ground potential upon the contact 226 and its corresponding contact in the bank to which the wiper 81 has access, thereby making the trunk line associated 80 with that contact busy. Accordingly, a circuit is completed for the winding 266 of starting relay 268 by way of wiper 225. Relay 268, upon energizing, closes a circuit for relay 269 and relay 270 in parallel at springs 282 and 283, and also closes a holding circuit 85 for winding 267 of the starting relay. Relay 269, upon energizing, disconnects battery 90 from the common relay 158 thereby preventing the operation of any other idle line switch in engagement with the shaft 230 95 during the time that 230 is moving. Relay 270, upon energizing, closes a circuit through high resistance winding of supervisory relay 66, and at the same time disconnects the locking arm 227 from the notch 100 228, thereby allowing the plunger shaft 230 to rotate in a counter-clock-wise direction by the tension of spring 293 until the locking plate 229 comes into contact with arm 290 which is secured to the plunger shaft 86 105 in such a manner that all the plungers of the idle line switches in engagement with shaft 230 are moved in a position before the terminals of the same trunk lines as the plungers engaged by the shaft 86. The bushing 110 292 carried on the vertical member 290^a of the arm 290 is so adjusted as to operate the springs mounted on the locking plate 229 just before the vertical member 290^a comes 115 into engagement with the locking plate 229. Reference is had to Fig. 5. The operation of spring 286 opens the holding circuit for winding 267 of starting relay 268, and also closes a circuit for winding 88 of starting relay 89 at springs 287. Relay 89, upon energizing, operates the plunger shaft 86 120 through the medium of relay 90 in the same manner as described above, to a position where the plungers engaged by the shaft 86 are standing before the terminals of the next 125 130

idle trunk line, while the plungers engaged by the shaft 230 will be standing before the terminals of the eighth trunk. Subsequent calls will now operate the master switch I in the manner described until the plungers engaged by the shaft 86 are in a position before the first trunk. Supposing the plungers engaged by the shaft 86 are standing before the terminals of the first trunk line, 10 and a secondary switch is operated to seize that line then a circuit is closed for winding 87 of starting relay 89 in the usual manner. Relay 89, upon energizing, completes a circuit for relay 91 through spring 93 closed by 15 arm 98, in parallel with the relays 90 and 61. Relays 61 and 90 operate and perform the same functions as described above. Relay 91, upon energizing, prepares a circuit for winding 267 of starting relay 268 and 20 closes a circuit for the solenoid 265, which now draws in its plungers to thereby rotate the shaft 86 and all the plungers of the idle line switch in a clock-wise direction to a position where the plungers are before the terminals of the tenth trunk. However, just 25 before the vertical member 290^a comes into engagement with locking plate 229, springs 288 are closed which completes a circuit for winding 267 of starting relay 268. Relay 268, upon energizing, completes a circuit for 30 the relays 269 and 270. Relay 269, upon energizing, disconnects battery from the common relay 163. Relay 270, upon energizing, disconnects the locking arm 227 from 35 its position in a notch in the locking plate 229, whereby the shaft 230 is rotated in a clock-wise direction by the solenoid 265 through the medium of arm 290 and locking plate 229. Although the circuit of relay 91 40 is at once broken as soon as the arm 98 moves, its springs are held in an operated position by the detent 92 until the idle plungers are standing before the terminals of the tenth trunk in which case the detent 45 is disengaged by the arm 99. And as a result of the springs of relay 91 separating, the circuit for winding 267 of starting relay 268 is opened; therefore, the idle plungers engaged by the shaft 230 will remain before 50 the terminals of the tenth trunk unless that trunk is busy. By the operation of springs 286 on the locking plate 229 a holding circuit was closed for winding 88 of starting relay 89. The relay 89 accordingly remains 55 operated and causes the shaft 86 to be actuated through the medium of relay 90 in the same manner as described above to a position where the idle plungers are before the next idle trunk line.

60 Suppose the idle plungers engaged by the shaft 86 are before the terminals of the first trunk line, and the idle plungers engaged by the shaft 230 are in a position before the terminals of the second trunk line in which 65 case the operation of a secondary switch

whose plunger is engaged by shaft 230 will cause the shaft to move to a position where all the idle plungers are before the terminals of the first trunk line. The operation of spring 289 by the arm 291 opens a point in the circuit of winding 88 of starting relay 89. Therefore, the shafts 86 and 230 remain in that position until any one of the secondary switches are operated to seize that trunk line, in which case the master switch I will 75 operate as previously described.

The operation of the chain relays 231, 232, 240, etc. as hereinbefore described shorts the resistance coils 271, 272, 280, etc. respectively in the circuit of differential relay 295. The 80 relay 295 is so adjusted that it will operate its armature when only one of the resistance coils is connected in series with its right hand winding and will release its armature when two or more of the resistance coils are 85 connected in series with said winding, for the purpose of opening a point in the circuit of winding 88 of starting relay 89, also a point in the holding circuit of winding 90 267 of starting relay 268, so that all the idle 95 plungers will be before the terminals of the same idle trunk line when any nine of the trunk lines become busy. Thus it will be seen that when only one trunk line in the group is idle, there will be only one of the 95 relays 231, 232, 240 etc. deenergized, and therefore relay 295 will operate to prevent the shaft 82 from moving its plungers away from the idle trunk line in an attempt to move them opposite a second idle trunk line 100 when no other idle trunk line is to be found.

When the last trunk accessible to the line switches D, D', etc., becomes busy, the last open point in the circuit of stop relay 65 is closed through springs 241, 242, 250, etc., 105 whereupon relay 65 energizes and disconnects battery at springs 64 from the relays of the master switch I with the exception of the start relay 87, from the relays 269 and 270, Fig. 2, and from the solenoid 265 of the master switch I. This prevents any operation at this time of the solenoid of the master switch I and prevents also the energization of the relays named. At springs 261, 110 stop relay 65 places ground through springs of the relay 262 (which is normally energized through springs 95 and 94 of the start relay 89) on the common conductor 263 with a result to be pointed out below.

As a further result of the last trunk becoming busy, circuits are closed for the two starting relays 268 and 89, whereupon these relays both energize. Relay 268 opens at springs 281 and 282 the circuit of the normally energized relay 160, whereupon relay 120 125 160 falls back and grounds the associated common conductor, thereby rendering busy all the idle line switches controlled by the shaft 230. Start relay 89, upon energizing, opens at springs 95 and 94 the circuit for the 130

normally energized relay 60, whereupon relay 60 falls back and grounds the associated common battery supply conductor at its left hand armature springs, thereby making busy 5 all the idle line switches controlled by the shaft 86. Relay 60 also removes ground at springs 262 from the common conductor 263. Accordingly, the result of the placing of ground on conductor 263 by relay 65 is that 10 a momentary impulse is transmitted over conductor 263 to the common conductor 264. The effect of this impulse of current is to cause all primary master switches to sweep over all their trunks to pick up all idle primary line switches that have not been previously picked up, i. e., engaged by the shaft, 15 after having become idle. Specifically, when conductor 264 is grounded, relay 100 of the master switch I pulls up and locks itself energized through contacts on the trip relay 44 and it remains operated until trip relay 44 pulls up, which it does in due time because the upper springs of the trip relay 100 are in multiple with the springs 20 of start relay 39, at which time relay 100 is unlocked and allowed to fall back on account of the fact that the original impulse is terminated by this time. When trip relay 44 pulls up, the circuit of solenoid 47 is 25 closed with the hereinbefore described results.

It will be apparent that since the line switches under the control of the master switch I are now made busy by relays 60 and 30 160, the primary master switches will be forced to come to rest in some position other than opposite trunk lines leading to this particular secondary group.

From the foregoing it will be seen that 40 I have devised a system in which a plurality of non-numerical switches are used, the secondary switches being so arranged that it is possible for two switches in the same group to establish connection with two 45 trunk lines at the same time.

While I have shown and described my invention in connection with one particular type of automatic switches, it will, of course, be understood that I do not wish to limit 50 myself to the precise form shown, but I desire on the contrary to include and have protected by Letters Patent all forms and modifications thereof which may come within the scope of the appended claims.

55 What I claim as my invention is:—

1. In a telephone system, trunk lines, an individual trunking switch for each trunk line, a master switch for controlling said individual switches adapted to preselect two 60 idle trunks, and means for operating two of said individual switches simultaneously to seize two trunks.

2. In a telephone system, subscribers' 65 lines, trunk lines, an individual trunking switch for each trunk line, a master switch

for controlling said individual switches, adapted to preselect two idle trunks ahead of the calls, and means for operating two of said individual switches simultaneously to seize two trunks. 70

3. In a telephone system, subscribers' lines, an individual trunking switch for each line, a plurality of secondary trunking switches, a master switch for controlling said secondary switches, adapted to preselect two idle trunks ahead of calls, means when the master switch is at rest for operating one of said secondary switches to seize a trunk, and means for operating another one of said secondary switches to seize a second trunk at the same time. 75

4. In a telephone system, subscribers' lines, an individual trunking switch for each line, a plurality of secondary trunking switches, a master switch for controlling said secondary switches, adapted to preselect two idle trunks ahead of calls, means when the master switch is at rest for operating one of said secondary switches to seize a trunk, means for operating another one of said secondary switches to seize a second trunk at the same time, and means to prevent the seizure of a trunk line while said master switch is operating. 80

5. In a telephone system, subscribers' lines, 85 an individual trunking switch for each line, a plurality of secondary trunking switches, a master switch for controlling said secondary switches, adapted to preselect two idle trunks ahead of calls, means for operating a secondary switch to seize a trunk line and automatically operate said master switch to preselect idle trunks, and means to limit at times the preselecting operation of said master switch when a secondary switch is 90 operated to seize a trunk line. 95

6. In a telephone system, a plurality of trunk lines, non-numerical trunking switches, a master switch for controlling said non-numerical switch, adapted to preselect idle trunks, and means whereby more than one of said non-numerical switches may be operated simultaneously to seize different 100 trunk lines. 110

7. In a telephone system, a plurality of 115 trunk lines, non-numerical trunking switches divided into groups and sub-groups, a master switch for controlling said non-numerical switches in one group whereby the non-numerical switches in one of said sub-groups have access to an idle trunk line and the non-numerical switches in another of said sub-groups have access to a second idle trunk line. 120

8. In a telephone system, a group of 125 trunk lines, non-numerical trunking switches divided into groups, a master switch for controlling said non-numerical switches, whereby the non-numerical switches in one group have access to one of said trunk lines, and 130

- the non-numerical switches in another group have access to another one of said trunk lines.
9. In a telephone system, a group of trunk lines, non-numerical trunking switches divided into groups, a master switch for controlling said non-numerical switches adapted to preselect two idle trunks, means for operating any one of said non-numerical switches in one sub-group to seize one of said trunk lines, and means for operating any one of said non-numerical switches in another group to seize another one of said trunk lines.
10. In a telephone system, the combination of a non-numerical switch having sets of passage contacts and a plurality of contact makers mounted to interconnect said passive contacts with a master switch for controlling said non-numerical switch adapted to pre-select a set of said contacts and to preselect a second set of said contacts, and means for operating a plurality of said contact makers at the same instant to interconnect the contacts so selected.
11. In a telephone system, a group of trunk lines, contacts serving as terminals of incoming trunk lines and outgoing trunk lines, means for preselecting the contacts of an idle outgoing trunk line and for pre-selecting the contacts of a second idle outgoing trunk line in the same group, and means for interconnecting the contacts so selected at the same instant.
12. In a telephone system, non-numerical trunking switches, a plunger for each switch, a first plunger controlling shaft, a second plunger controlling shaft, automatic means for rotating said first shaft to move a part of said plungers responsive to the rotation of said second shaft, and means for rotating said second shaft independently of said first shaft to move a part of said plungers.
13. In a telephone system, trunk lines, a non-numerical switch for connecting with said trunk lines, a plunger for said switch controlled by a plunger shaft, another non-numerical switch having direct access to the same trunk lines, a plunger for said other switch controlled by another plunger shaft, and a master switch for controlling said shafts to maintain the plunger controlled by said first shaft in a position before the terminals of one trunk line, and the plunger controlled by said second shaft in a position before the terminals of another trunk line.
14. In a telephone system, trunk lines, non-numerical switches for interconnecting said trunk lines, a master switch for controlling said non-numerical switches adapted to preselect idle trunks, a chain relay energized upon the seizure of each trunk line,
- another relay for controlling the operation of said master switch, said other relay operated when only one of said chain relays remains in normal position.
15. In a telephone system, trunk lines, non-numerical switches for interconnecting said trunk lines, a master switch for controlling said non-numerical switches adapted to preselect idle trunks, a chain relay energized upon the seizure of each trunk line, another relay for controlling the operation of said master switch, said other relay operated when only one of said chain relays remains in normal position and released when two of said relays are in normal position.
16. In a telephone system, trunk lines, non-numerical switches for interconnecting said trunk lines, a master switch for controlling said non-numerical switches adapted to preselect idle trunks, a chain relay energized upon the seizure of each trunk line, another relay for controlling the operation of said master switch, said other relay operated when only one of said chain relays remains in normal position and released when any two of said relays are in normal position, and a third relay for further controlling the operation of said master switch energized when all of said chain relays are energized.
17. In a telephone system, trunk lines, non-numerical switches for interconnecting said trunk lines, a master switch for controlling said non-numerical switches, adapted to preselect idle trunks, a first relay for controlling the operation of said master switch, a normally closed circuit for said relay including a plurality of resistance coils in series, another relay energized upon the seizure of a trunk line, whereby one of said resistance coils is shorted, said first relay operated when only one of said resistance coils is included in said circuit and released when any two of said resistance coils are included in said circuit.
18. In a telephone system, trunk lines, a non-numerical switch for interconnecting said trunk lines, a plunger for said switch controlled by a plunger shaft, another non-numerical switch, a plunger for said switch controlled by another plunger shaft, a master switch for controlling said shafts whereby the plungers controlled by said first shaft are in a position before the terminals of a trunk line, and the plungers controlled by said second shaft are in a position before the terminals of another trunk line, and means for operating any one of said plungers controlled by said second shaft while said first shaft is moving.
19. In a telephone system, trunk lines, a non-numerical switch for interconnecting said trunk lines, a plunger for said switch

controlled by a plunger shaft, another non-numerical switch, a plunger for said shaft controlled by another plunger shaft, a master switch for controlling said shafts whereby the plungers controlled by said first shaft are in a position before the terminals of a trunk line, and the plungers controlled by said second shaft are in a position before the terminals of another trunk line, and means for operating any one of said plungers controlled by said first shaft while said second shaft is moving.

20. In a telephone system, trunk lines, a non-numerical switch for interconnecting said trunk lines, a plunger for said switch controlled by a plunger shaft, another non-numerical switch, a plunger for said switch controlled by another plunger shaft, a master switch for controlling said shafts whereby the plungers controlled by said first shaft are in a position before the terminals of a trunk line, and the plungers controlled by said second shaft are in a position before the terminals of another trunk line, means for operating any one of said plungers controlled by said second shaft while said first shaft is moving, and means to prevent the operation of any of said plungers controlled by said first shaft while the same is moving.

30. 21. In a telephone system, trunk lines, automatic switches for connecting with said trunk lines, means for positioning a group of automatic switches in alignment with an idle trunk and means for positioning a second group of automatic switches in alignment with a second idle trunk of the same group of trunks, means for operating an automatic switch in said second group to connect said second trunk line before said first idle trunk is connected with, and for actuating said second group positioning means.

22. In a telephone system, a group of trunk lines, automatic switches having access to and for connecting with all the trunk lines of said group, preselecting means maintaining two trunk lines in the said group selectable at the same time, and means for operating two of said switches simultaneously to seize the two preselected trunks.

23. In a telephone system, trunk lines, automatic switches for connecting with said trunk lines, a master switch which operates to preselect two idle trunk lines for said automatic switches, and means for preventing operation of the master switch to preselect idle trunks when all of said trunk lines are busy.

24. In a telephone system, trunk lines, automatic switches divided into groups for connecting with said trunk lines, a master switch for controlling said automatic switches which operates to preselect two idle trunk lines, one for each group when two

or more trunk lines are idle and which operates to preselect the same idle trunk line for both groups when all the remaining trunk lines are busy. 65

25. In a secondary trunking system comprising secondary line switches and trunk lines accessible thereto, a control circuit, resistances equal in number to the number of said trunk lines included in said circuit in series, a relay individual to each trunk line for short circuiting the associated resistance, and a marginal relay included in said circuit and adjusted to operate when all but one of said resistances are short circuited. 70

26. In a secondary trunking system comprising secondary line switches and trunk lines accessible thereto, a control circuit, resistances equal in number to the number of said trunk lines included in said circuit in series, a relay individual to each trunk line for short circuiting the associated resistance, and a marginal relay included in said circuit, said marginal relay being adjusted to operate when all but one of said resistances are short-circuited, and to fall back when two or more of said resistances are not 80 85 short circuited. 90

27. In a telephone system, a master switch comprising two mechanically cooperating but independently operable preselecting devices, trunk lines, a line switch having access to said trunk lines and controlled by one of said devices, a second line switch also having access to said trunk lines but controlled by the other of said devices, means for operating said devices to preselect trunk lines for their respective switches, and means for preventing said devices from maintaining the same trunk line preselected. 95 100

28. In a telephone system, a master switch comprising two cooperating but independently operable preselecting devices, trunk lines, a line switch having access to said trunk lines and controlled by one of said devices, a second line switch also having access to said trunk lines but controlled by the other of said devices, means for operating said devices to preselect trunk lines for their respective switches, and means effective in case one of said devices preselects a trunk line that is already preselected by the other 105 110 of said devices for re-operating said other device to preselect another trunk line. 115

29. In a telephone system, two automatic switches, trunk lines each accessible to both switches, preselecting means for the first switch for bringing it, while still idle, into operative relation to an idle one of said trunk lines, similar means for the second switch, and means for preventing both switches from remaining in operative relation to the same idle trunk line. 120 125

30. In a telephone system, a group of automatic switches, preselecting means com-

mon to such switches, a second group of automatic switches, preselecting means common to the second group, trunk lines each accessible to all of said switches, each of said preselecting means being effective to bring the idle ones of its own switches into operative relation to an idle trunk, and means for preventing the idle switches of both groups from remaining in operative relation to the same idle trunk.

31. In a telephone system, two automatic switches, trunk lines each accessible to both switches, preselecting means for the first switch for bringing it, while still idle, into operative relation to an idle one of said trunk lines, similar means for the second switch, means for preventing both switches from remaining in operative relation to the same idle trunk line, and means for rendering the last named means inoperative in case only one trunk remains idle.

32. In a telephone system, a group of automatic switches, preselecting means com-

mon to such switches, a second group of automatic switches, preselecting means common to the second group, trunk lines each accessible to all of said switches, each of said preselecting means being effective to bring the idle ones of its own switches into operative relation to an idle trunk, means for preventing the idle switches of both groups from remaining in operative relation to the same idle trunk, and means for rendering the last named means inoperative in case only one trunk remains idle.

33. In a switch which will automatically rotate its test wiper seeking an idle bank contact upon which to rest consequent to the contact upon which it is then resting becoming busy, automatically applied means for incapacitating the switch from rotating its said wiper when all other contacts normally accessible thereto are busy.

Signed by me at Chicago, Cook County, Illinois, this 19th day of June, 1918.

JOHN H. HOMRIGHOUS.
